UNITED STATES PATENT OFFICE.

ANDREW KENDECHY, OF CLEVELAND, OHIO.

LOCK.

Application filed April 12, 1922. Serial No. 551,806.

To all whom it may concern:

Be it known that I, ANDREW KENDECHY, a citizen of the United States, residing at Cleveland, in the county of Cuyahoga and State of Ohio, have invented new and useful Improvements in Locks (Case C), of which the following is a specification.

This invention relates to permutation locks and is an improvement upon Patent No. 1,415,651, granted to me May 9, 1922.

An object of the present invention is the provision of a permutation lock which includes a plurality of indicia carrying members for controlling the operation of a locking bolt and novel means for holding the indicia carrying members in position to permit of the release of the bolt, together with means for rearranging the relative positions of the indicia carrying members to change the lock combination.

With the above and other objects in view, the invention further includes the following novel features and details of construction, to be hereinafter more fully described, illustrated in the accompanying drawings and pointed out in the appended claims.

In the drawings:—

Figure 1 is a front elevation of a lock constructed in accordance with the invention and shown in applied position.

Figure 2 is an edge view of the same.

Figure 3 is a central sectional view showing the parts in locked position.

Figure 4 is a similar view showing the parts in released position, or in the position which permits of the operation of the locking bolt.

Figure 5 is a transverse sectional view with the cover of the lock casing removed and the parts in the position shown in Figure 3.

Figure 6 is a similar view with the parts in the position shown in Figure 4.

Figure 7 is an enlarged elevation of one of the indicia carrying members.

Figure 8 is a transverse sectional view of the same.

Figure 9 is a detail elevation of the bolt operating collar.

Figure 10 is an edge view of this collar.

Figure 11 is a detail sectional view of the cap.

Figure 12 is a like view of the hollow cylindrical post.

Figure 13 is a detail view of the lock operating member.

Figure 14 is a detail perspective view of the locking bolt.

Figure 15 is a detail elevation of the casing cover detached.

Figure 16 is a detail perspective view of the radially movable member.

Referring in detail to the drawings, wherein like characters of reference denote corresponding parts, the reference character 20 indicates a door or other movable member to which the lock is shown as applied, while 21 indicates a stationary member which may be provided with a keeper for engagement by a locking bolt, as will be hereinafter explained.

The lock which constitutes the present invention includes a casing 22, which is herein shown as of rectangular shape and provided along one side edge with an extended plate 23 for attachment to the edge of the door 20 as shown in Figure 2 of the drawings. This plate may form a part of the casing 22 or may be removably secured thereto as shown in Figures 5 and 6 of the drawings. This plate is provided with a removable cover 24 which is attached to the door 20 by means of screws 25 and which is provided with spaced slots 26 for the reception of lugs 27 extending from the edges of the walls of the casing 22, the said lugs and slots being equally spaced so as to permit the former to be received in any of the latter.

The bottom of the casing 22 is provided with a central opening and extending through this opening is a hollow cylindrical post 28 which is open at one end and has its other end provided with an annular flange 29 for engagement against the bottom face of the casing 22. Mounted upon the post 28 within the casing 22 is a collar 30 having a radially extending lug 31 projecting from its outer periphery. The lug 31 is adapted to engage a locking bolt 32 which is mounted for sliding movement through the casing 22 and which is provided with a reduced extension 33. This extension operates through an opening 34 provided in the plate 23 and is adapted to enter or engage a suitable keeper (not shown) secured to the adjacent face of the stationary member 21. When the bolt is in locking position, the lug 31 engages an inclined shoulder 35 formed on the bolt, while an oppositely inclined shoulder 36, also provided on the bolt, is adapted to be engaged by the lug 31 to retract the bolt, as illustrated in Figures 5 and 6 of the draw-

ings. In order to prevent rotation of the collar 30 when the bolt 32 is in the position shown in Figure 5 of the drawings, there is provided a spring actuated dog 37, which is pivotally mounted as shown at 38 and whose bill engages within a notch or a slot 39 provided in the collar 30.

Also mounted upon the hollow cylindrical post 28 but upon the outside of the casing 22 or cover plate 24 is a plurality of rotatable locking members 40 and 41. The member 40 is of a larger diameter than the member 41 and is positioned against the face of the cover plate 24, being of sufficient diameter to cover the slots 26. Each of the members 40 and 41 include an annulus which is provided with a flange 42 and which is surrounded by an indicia carrying ring 43 whose outer periphery is beveled as shown. The ring 43 engages over the flange 42 and is frictionally held against movement upon the annulus by means of a clamping ring 44, the latter clamping the ring 43 against the flange 42 through its threaded engagement with the annulus. Thus, by loosening the clamping ring 44, the indicia carrying ring may be rotatably adjusted upon the annulus 40.

Each annulus 40 is provided upon its inner periphery with a notch 45, while the hollow cylindrical post 28 is provided with an elongated slot 46, so that by rotating the annuli and with them the indicia carrying rings 43 and rotating the hollow cylindrical post, the notches 45 and slot 46 of the annuli and post respectively may be brought into register with the notch 39 of the collar 30, for a purpose hereinafter explained.

The hollow cylindrical post 28 extends beyond the outer annulus and has threadedly secured thereon a cap 47, the latter being provided with an indicia carrying beveled flange 48, which co-operates with the indicia carrying rings 43. The cover plate 24 is provided with graduations or numbers arranged in semi-circular form about the inner ring 43, as shown at 49 in Figure 1 and when the proper indicia, that is, the numbers or graduations upon the rings 43 and the proper letter or graduation upon the cap 47 are aligned with the proper number or graduation upon the cover plate 24, the notches 39, 45 and the slot 46 will be in register. The purpose of this is to permit the post 28, the rings 43 and the annuli 40 to be locked together for a simultaneous rotary movement and for the release of the dog 37 to permit the operation of the bolt 32. This is effected by means of a radially movable member 50, whose outer edge is normally positioned within the slot 46, but which is adapted to be projected through the slot to engage the notches 39 and 45 to lock the parts together and to force the bill of the dog 37 out of the

notch 39. The radially movable member 50 is provided upon its inner edge with inclined cam surfaces 51 which normally contact with similar surfaces 52 provided upon the periphery of a member 53 which is located within the hollow cylindrical post 28 and which is movable axially of said post. The inclined cam surfaces 52 of the member 53 are of annular formation, so that the said member 53 may be rotated. A guide pin 54 extends into the hollow cylindrical post 28 and enters a guide opening 55 extending inwardly from the inner end of said member 53. The latter extends through an opening in the cap 47 and is provided with an operating knob 56, while a collar 57 is threaded upon the member 53 to limit the outward movement of the latter. The member 50 is held longitudinally centered on the member 53 by means of a spring 57' which extends through an opening 58 provided in said member 50.

After the slot 46 and notches 39 and 45 have been moved into register in the manner previously explained, the member 53 may be moved axially from the position shown in Figure 3 to the position shown in Figure 4 so as to project the member 50 radially to lock the parts together and move the dog 37 out of engagement in the notch 39, whereupon the cap 47 may be rotated to rotate the collar 30 and move the locking bolt from the position shown in Figure 5 to the position shown in Figure 6. After the locking bolt has been again moved to locking position, the member 53 may be moved inward to permit of the retraction of the radially movable member 50, whereupon the indicia carrying members may be independently rotated and operation of the lock prevented except by persons familiar with the combination. The cap 47 is milled or serrated as shown in Figure 2 to facilitate rotation, while the locking rings 44 are likewise milled or serrated.

The combination lock may be changed by releasing the rings 43 and rotating the same so as to bring a different number or division opposite the notches 45.

Located within the casing 22 are spaced stationary contacts 59, which are adapted to be engaged or secured to conductor wires (not shown) passed through openings 60 provided in the casing. The contacts 59 are arranged in pairs and may be included in separate circuits connected to signals or alarms at different places. The collar 30 has extending partly around its outer periphery an arcuate shaped insulating flange 61, which carries spaced spring contact arms 62. These contact arms are adapted to bridge the stationary contact members 59 for the purpose of closing the circuit within which these members are included.

The invention is susceptible of various

changes in its form, proportions and minor details of construction and the right is herein reserved to make such changes as properly fall within the scope of the appended 5 claims.

Having described the invention what is claimed is:—

1. A permutation lock comprising a casing, a locking bolt operating therein, a hollow cylindrical member mounted for rotation within the casing and extending beyond one wall thereof, a collar mounted for rotation within the casing upon the hollow cylindrical member, means for holding the collar against movement, means for operatively connecting the latter and the locking bolt, whereby rotation of the collar will operate the bolt, a plurality of indicia carrying members mounted for rotation upon the hollow cylindrical member upon the outside of the casing, means including an operating knob, whereby all of the indicia carrying members may be locked together and means whereby the indicia carrying member locking means 10 will release the collar holding means to permit of the operation of the locking bolt.
2. A permutation lock comprising a casing, a locking bolt operating therein, a hollow cylindrical member mounted for rotation within the casing and extending beyond one wall thereof, a notched collar mounted for rotation within the casing upon the hollow cylindrical member, a spring actuated dog engageable within the notched collar to hold the latter against movement, means operatively connecting the collar and locking bolt, whereby rotation of said collar will operate the bolt, a plurality of indicia carrying members mounted for rotation upon the hollow cylindrical member upon the inside of the casing, means including an operating knob, whereby all of the indicia carrying members may be locked together and means whereby the indicia carrying member locking means 15 will engage and operate the spring actuated dog to release the collar and permit of the operation of the locking bolt.
3. A permutation lock comprising a casing, a locking bolt operating therein, a hollow cylindrical member mounted for rotation within the casing and extending beyond one wall of the latter, a collar mounted for rotation within the casing upon the hollow cylindrical member, means for holding the collar against movement, means operatively connecting the collar and the locking bolt whereby rotation of said collar will operate the bolt, a plurality of indicia carrying members mounted for rotation upon the hollow cylindrical member upon the outside of the casing, each of said members comprising a 20 flanged annulus, an indicia carrying ring adjustable upon the collar, a clamping ring threadedly engaging the annulus to frictionally hold the indicia carrying ring in position, means including an operating knob, whereby all of the indicia carrying members may be locked together and means whereby the indicia carrying member locking means 25 will release the collar holding means to permit of the operation of the locking bolt.
4. A permutation lock comprising a casing, a locking bolt operating therein, a hollow cylindrical member mounted for rotation within the casing and extending beyond one wall thereof, a collar mounted for rotation within the casing upon the hollow cylindrical member, means for holding the collar against movement, means operatively connecting the collar and the locking bolt, whereby rotation of the collar will operate the bolt, a plurality of indicia carrying members mounted for rotation upon the hollow cylindrical member upon the outside of the casing, each of said members comprising a 30 flanged annulus, an indicia carrying ring adjustable upon the annulus, a clamping ring threadedly engaging the annulus to frictionally hold the indicia carrying ring in position, means including an operating knob, whereby all of the indicia carrying members may be locked together, means whereby the operating knob will prevent adjustment of the indicia carrying ring when the latter is 35 in locked position and means whereby the indicia carrying member locking means will release the collar holding means to permit of the rotation of the locking bolt.
5. A permutation lock comprising a casing, a locking bolt operating therein, a hollow cylindrical member mounted for rotation within the casing and extending beyond one wall thereof, a collar mounted for rotation within the casing upon the hollow cylindrical member, means for holding the collar against movement, means operatively connecting the collar and the locking bolt, whereby rotation of said collar will operate the bolt, a plurality of indicia carrying members mounted for rotation upon the hollow cylindrical member upon the outside of the casing, a radially movable member engageable with the indicia carrying members for locking the latter together, an axially movable operating member and cam engaging surfaces between the operating member and radially movable member, whereby movement of the former will operate the latter to release the collar holding means and permit of the operation of the locking bolt.

In testimony whereof I affix my signature.
ANDREW KENDECHY.
